4 Claims. (Cl. 25—61)

This invention relates to a continuously operating sliding press provided with a rectilinearly reciprocating press table guided in the carriage.

Continuously operating presses of the revolving table type are known already, but they require at least six to eight molds to attain a somewhat satisfactory output. This is a serious drawback, since molds are very expensive and their relatively large number prolongs in a highly uneconomical manner the necessary alteration work when a change in the form of the product has to be made.

According to the invention, the advantages afforded by revolving table presses and consisting in combining all operations, such as filling, preliminary pressing, airing, final pressing, and ejecting, into a single continuous process are attainable also by ordinary table presses in a surprisingly simple manner. In some known table presses provided with a reciprocating mold the various operations, such as filling, pressing, ejecting, and discharging, take place during the motion of the mold truck by utilizing the devices found in revolving table presses for causing the various movements. This combination of the various steps into a single operation is the only advantage which these presses have in common with revolving table presses. They fail, however, to comply with the most important requirements which a modern heavy duty press has to meet, namely, large output at a minimum of attendance and power consumption.

The invention fully complies with this requirement in a novel way by proposing a combination of an ordinary table press with a revolving table press, which retains the advantages of both constructions without their defects, the ordinary press supplying the simple construction and the revolving table press the continuous succession of operations. New is the provision of two press boxes arranged in tandem and moving to and fro like a slide. Owing to this arrangement, the time elapsing between the various pressing steps and hitherto not made use of is advantageously utilized for other operations, such as filling, preliminary pressing, airing, ejecting and the like. However, the invention covers more than the arrangement in tandem of two press boxes, since this feature alone would not suffice to produce the large output required in order to attain the high degree of economy aimed at. This object is fully attained by additional labor-saving devices. The cooperation of the two press tables is perfected so as to form a continuous operation by means of

an interposed band conveyor which receives by turns the finished articles, so that attendance of the press is reduced to the removal of the pressed articles at stated intervals. This regular working method, which is identical with that of an automatic revolving table press makes it possible for the sliding press according to the invention to attain a greater output than ordinary table presses at a power consumption that is smaller than that required for revolving table presses. A further advantage is the extraordinarily simple and clearly arranged structure of the press whereby attendance is considerably simplified and repairs are practically eliminated.

In addition to these main constructional features, a number of other structural arrangements were required to insure perfect operation of the press which may be driven hydraulically or in any other mechanical manner so as to produce, in certain cases, some motions and compressive forces in a separate way either hydraulically or mechanically.

By way of example, the invention is illustrated in the accompanying drawing, in which Figures 1 and 2 are views of a press embodying the invention and Figs. 3 to 6 show the filling process.

Referring to the drawing, 1 is the top cross beam and 2 the bottom cross beam of the press, in which the press pistons 3 and 4 are arranged in known manner by the equalization of hydraulic or mechanical pressure. 5 and 6 are traverses fitted with the carriage guide 7 and rigidly connecting the top and bottom cross beams. 8 is the press table in which the pistons 9 and 10 and the conveyor 11 for receiving the pressed articles are disposed, the table 8 being constructed as carriage which is guided in the guides 7 of the traverses 5 and 6. The table 8 has two or more openings for the reception of the pulverulent mass to be pressed and carries also the filling boxes 12 which, with their pushing ledges 13, are arranged so that the latter can advance in a direction opposite to that of the table. The table 8 is reciprocated by hydraulic or mechanical drive or by a suitable combination of both modes of driving.

The lower press path comprises the filling paths 14, the preliminary pressing and ejecting paths 15, and the press piston 4, the preliminary pressing and ejecting path being constructed so as to serve alternately for preliminary pressing and ejecting by mechanical or hydraulic release. Preliminary pressing takes place at the

hinged paths 16 when the path 15 has been released downwardly. The upper pressing path consists of the lifting or delivery paths 17 of the upper table pistons 9 and of the press 5 piston 3.

When the mold 18 has been provided with pulverulent mass by the filling box 12, the press table is advanced in the direction of the arrow shown in Fig. 1. The upper table piston 9, 10 shown in left-hand position, will then roll off from the cam 17 and drop down from a certain height, so that its ram is forced to enter the mold and compress the mass contained therein. This step represents the first preliminary pressing and airing of the mass which, according to 15 its nature, may be subjected to repeated preliminary pressing and airing operations by lengthening the press table and providing a plurality of curved paths 17 arranged one behind the other. 20

The lower table piston 10, when in left-hand position, is lifted by the path 16. The lower pressing ram enters the mold and by the weight of the upper table piston compresses the mass still further until the lower piston 10 lifts the pressed article with the upper table piston 9 resting thereon to such an extent that the article will emerge a few millimeters from the mold 18 to afford the air contained within it another opportunity of escape. When the lower table piston 10 moves off from the path 16 it will recede until its pressure roll rests on the pressure path of the press piston 4 and the pressed article is thus aired again, this time in 35 an indirect manner. This step concludes the second preliminary pressing and airing operation to which the pressed article is subjected.

During further advance of the press table 8 the inclined press paths of the pistons 3 and 4 40 bring it about that the rams of the lower and upper table pistons 9 and 10 enter more deeply into the mold and, by applying pressure from both sides, compress the contents thereof to a certain height. Pressing is continued at a certain pressure until the table pistons 9 and 10 45 (left-hand position) have attained the central position of the pistons 3 and 4 shown in Fig. 1. When this position has been reached the main pressure has been applied. The motion of the press table in the opposite direction causes then the same pressing process to be repeated, so that at each advance and return motion of the table whereby the lower table pistons 10 and the upper table pistons 9 are alternately brought 50 into the central position of the pistons 3 and 4 a pressed article will be produced.

The reciprocatory motion of the press table 8 is possible, however, only because the paths 15, 60 by mechanical or hydraulic control, act one time as preliminary pressing path, as indicated in Fig. 1, left-hand position, and then again as ejecting path, as shown in Fig. 1, right hand position.

The pressed article is ejected by causing the lower table piston 10 to move up by means of the path 15 adjusted to ejecting position, as indicated in Fig. 1, right hand position, and to raise the pressed article together with the upper table piston resting thereon until the ram of the lower table piston 10 is flush with the top edge of the table 8, whereupon the upper table piston 9 is lifted by the curved path 17. Being now exposed, the pressed article is caught during the raising of the upper table piston 9 by 75 the pushing ledges 13 when the table 8 advances

still further, and pushed upon the conveyor 11 for removal.

As soon as the pressed article has been removed to the extent of one-half from the ram of the lower table piston 10, the latter will move 80 from the ejecting path 15, right hand position, back again to the filling path 14 and thus release the mold for refilling.

In the known presses the molds were filled with pulverulent mass either by causing the filling box to pass repeatedly over the stationary mold or moving the mold under the stationary filling box. These filling methods, however, particularly in case of ceramic masses which are difficult to work, always lead to one-sided filling 85 of the mold, since one-sided motion of the filling box or mold causes the mass to be fed to the mold at different height and density, so that the mold is charged unevenly and on one side only. Simultaneously, as the reciprocating motion of the filling box when the mold is stationary or of the mold when the box is stationary has to be repeated several times in order to insure a somewhat uniform filling of the mold, these processes involve a considerable 90 loss in time, which appreciably lessens the output of the presses.

To insure unvarying accuracy in filling the molds at uniform mass distribution and density the invention provides that the reciprocatory 105 motion of the mold is accompanied by a reciprocatory motion of the filling box above the mold, so that during the filling step the mold as well as the filling box will be in motion and thus bring about uniform distribution of the 110 mass.

The filling process is shown in Figs. 3 to 6. As soon as the mold 18, after ejection of the pressed article, has been advanced one-half under the filling box 12, as indicated in Fig. 3, 115 the filling box begins to move while the mold moves in opposite direction, and passes over the mold until the positions shown in Figs. 4 and 5 have been reached. Then the mold 18 changes its direction of motion, and simultaneously, the 120 filling box returns to its normal position and passes again over the mold, though in opposite direction, while both the mold and the box are in motion, as indicated in Figs. 5 and 6. In this way uniform filling of the mold at equal 125 mass distribution and density on the sides 19 of the mold is attained.

I claim:—

1. A press of the character described comprising a carriage, a press table guided for movement on said carriage, means to impart rectilinearly reciprocatory movement to said table, a pair of press boxes carried by said table and arranged one behind the other, and a series of means operable during the movement of said 135 table for filling the boxes with material, preliminarily pressing the material in the boxes, preliminarily airing the material, further pressing of the material, a further airing of the material, final pressing of the material, and ejecting and discharging the molded material from the boxes.

2. A press according to claim 1 having a band conveyor for removing the pressed article arranged between the boxes.

3. A press according to claim 1 having a band conveyor for removing the pressed articles arranged between the boxes, and pistons disposed on both sides of the press-table for compressing the content of the mold, the upper piston acting 150

upon the material by dropping down and subjecting the content of the press boxes to the desired number of preliminary pressing and airing operations, the lower piston performing the 5 final pressing.

4. A press according to claim 1 having a band conveyor for removing the pressed articles ar-

ranged between the boxes, the press having an upper and a lower pressing path, a part of the lower pressing path serving alternately as preliminary pressing and as ejecting path, its motion being controlled mechanically.
